CARBOXYLIC ACIDS ALPHA-SUBSTITUTED BY AT LEAST ONE CYCLIC RADICAL

Etienne Szarvasi, Lyon, and Liliane Neuvy, Paris, France, assignors to Lipha, Lyonnaise Industrielle Pharmaceutique

No Drawing. Filed Feb. 21, 1962, Ser. No. 174,684
Claims priority, application France, Feb. 23, 1961, 853,642, Patent 1,289,597; Apr. 28, 1961, 860,401, Patent 80,103; May 16, 1961, 862,174, Patent 1,318; Jan. 23, 1962, 885,619, Patent 1,289,597
26 Claims. (Cl. 260—347.4)

The present invention concerns new carboxylic acids alpha-substituted by at least one cyclic radical, some of their derivatives and their processes of production.

Some new aliphatic acids disubstituted by cyclic, phenyl, furyl or tetrahydrofuryl radicals, and their derivatives have formed the subject of French Patent No. 1,278,631 of July 29, 1960.

The compounds of the present invention differ therefrom in that they comprise a substituent consisting of a 1-naphthyl or 1-naphthylmethyl radical and either another substituent consisting of a furyl or tetrahydrofuryl radical, or an olefine chain. They consist of alpha-substituted acids of the general formula

in which:

n is an odd number at most equal to 3,
 R_1 is a member of the group comprising the 1-naphthyl and 1-naphthylmethyl radicals, and
 R_2 is a member of the group comprising the furyl and tetrahydrofuryl radicals and—when n denotes the number 1 and R_1 the naphthyl radical—the vinyl and 1-propenyl radicals, as also their sodium salts, their alkyl and dialkylaminoethyl esters, their hydrazides and their 2-amidoethanol derivatives, and the corresponding ethyl malonates, nitriles and amides.

These acids may be prepared in accordance with the invention by either of the following two methods, whereby they are obtained in good yields.

In the first method, a disubstituted alkyl malonate of the general formula

in which n , R_1 and R_2 have the same meanings as before and R is a lower alkyl radical, is saponified and decarboxylated by means of an alkali in the presence of an alcohol, preferably benzyl alcohol.

The above disubstituted alkyl malonates are preferably obtained by reaction of a sodium alcoholate with an alkyl malonate mono-substituted by one of the radicals R_1 and R_2 ($CH_2)_n$, followed by condensation of the sodium derivative obtained with the halide of formula $R_2(CH_2)_nX$ or R_1X , in which X denotes chlorine or bromine, depending upon whether the radical already attached to the alkyl malonate is R_1 or $R_2(CH_2)_n$.

Disubstituted ethyl malonates of the formula

in which n , R_1 and R_2 have the same meanings as before, are new compounds.

2

In the second method, alpha-substituted aliphatic acids of the formula

in which n , R_1 and R_2 have the same meanings as before, are prepared by hydrolysing an alpha-substituted nitrile of the formula

by means of an alkali in the presence of an alcohol, preferably benzyl alcohol. In a preferred variant of the invention, in the case of the use of benzyl alcohol, alkali and nitrile are employed in equimolecular quantities. The above nitriles are preferably obtained by treatment of nitrile of the general formula R_1CH_2CN or

with sodamide, followed by condensation of the sodium derivative obtained with the halide of the general formula $R_2(CH_2)_nX$ or R_1X , depending upon whether the nitrile is of formula R_1CH_2CN or $R_2(CH_2)_nCH_2CN$.

Alpha-substituted nitriles of the formula

in which n , R_1 and R_2 have the same meanings as before, are new compounds.

The sodium salts and the alkyl and dialkylaminoethyl esters of the preceding acids are obtained by neutralisation or esterification of the corresponding acids, which thus constitute intermediate products in the preparation of their derivatives.

In addition, it is possible to obtain by hydrolysis of the nitriles, not the above-mentioned acids, but the corresponding amides of formula

the hydrolysis of the nitrile being effected by a substantially equimolecular quantity of an alkali in the presence of alcohol. Amides of the formula

in which n , R_1 and R_2 have the same meanings as above, themselves constitute new compounds.

Hydrazides of the formula

in which n , R_1 and R_2 have the same meanings as before, are also new compounds. They are obtained by reacting an ester of the corresponding acid with hydrazine.

Finally, 2-amidoethanol derivatives of the formula

are also new products, which are prepared by reacting an ester of the corresponding acid with monoethanolamine.

The above-defined acids, their sodium salts and their

esters, as also their amides, exhibit hypocholesterolaemic and choleric properties. The following Table I indicates the compared activities of alpha-biphenylbutyric acid, which is a known very active anticholesterolaemic compound, and of various compounds of the application, in relation to the lowering of the cholesterol, lipid and lipoprotein content of the blood, on series of rats rendered hypercholesterolaemic by the chemical product known under the trademark "Triton." "Triton" is defined in The Merck Index, Seventh Edition, as being p-isoctylpolyoxyethylenephenoxy. The products were administered intraperitoneally in a dosage of 150 mg./kg. The administration of the product by the oral route in a dosage of 300 mg./kg. gives substantially identical results.

TABLE I

	Cholesterol coefficient	Lipid coefficient	Lipoprotein coefficient
Alpha-biphenylbutyric acid	100	100	100
Sodium alpha-(1-naphthyl)-furylpropionate	120	186	282
Sodium beta-(1-naphthyl)-beta-furylisobutyrate	97	122.5	141.6
Sodium alpha-(1-naphthyl)-tetrahydrofurylpropionate	110.4	60	26.6
Sodium alpha-(1-naphthyl)-methyl tetrahydrofurylvalerate	30	57	56
Sodium alpha-(1-naphthyl)-hexen-delta-4-oate	52	36	22

It will be seen that the first of the above-designated new compounds are notably more active than alpha-biphenylbutyric acid. The others, while being less active, still have interesting efficacy.

The toxicities of the compounds of the invention, expressed by the 50% lethal dose orally or intraperitoneally administered in the rat, are the following (in mg./kg.):

	Oral route	Intra-peritoneal route
Sodium alpha-(1-naphthyl)-furylpropionate	1,500	300
Sodium beta-(1-naphthyl)-beta-furylisobutyrate	1,500	300
Sodium alpha-(1-naphthyl)-tetrahydrofurylpropionate	750	300
Sodium alpha-(1-naphthylmethyl) tetrahydrofurylvalerate	1,500	350
Sodium alpha-(1-naphthyl)-hexen-delta-4-oate	1,500	250

By way of comparison, the toxicity of alpha-biphenylbutyric acid is 1500 mg./kg. by the oral route.

The above acids and sodium salts, mixed with or dissolved in appropriate excipients and adjuvants, may be administered for the treatment of atherosclerosis in dosages between 0.010 g. and 2 g. per day by the oral, rectal or parenteral route.

The dialkylaminoethyl esters possess a therapeutic anti-inflammatory activity. In addition, the diethylaminoethyl ester of alpha-1-naphthylhexen-delta-4-oic acid possesses psychoenergetic activity which is useful in the treatment of traumatic conditions, which is much greater than that of the dimethylaminoethyl ester of para-chlorophenoxyacetic acid, which is a known therapeutic compound. The diethylaminoethyl ester of 1-naphthylpenten-delta-4-oic acid exhibits in the Magnus test on the isolated intestine of the rabbit a spasmolytic activity which is ten times greater than that of papaverine.

The hydrazides constitute intermediate products in the synthesis of the substituted hydrazines described in the French patent application of December 11, 1961, in the name of the applicants, which constitute inhibitors of monoaminoxydase and coronary vasodilators.

Finally, the 2-amidoethanol derivatives possess therapeutic hypoglycemic properties.

There are hereinafter described as non-limiting ex-

amples the preparations and physical properties of various compounds of the invention.

Example 1.—Ethyl alpha-(1-naphthylmethyl)alpha-furylmalonate

Empirical formula: $C_{23}H_{24}O_5$. (Molecular mass: M=380.42.) Developed formula:

Sodium ethoxide is prepared by introducing 9 g. (0.4 atom) of sodium into 256 cc. of absolute ethanol. There are added thereto 96 g. (0.4 mol.) of ethyl furfurylmalonate, and the mixture is boiled for 5 minutes while being well stirred. After cooling, 70.4 g. (0.4 mol.) of 1-chloromethylnaphthalene are added drop-by-drop through a dropping funnel, whereafter the mixture is heated under reflux for 24 hours and extracted with benzene.

Distillation of the extract gives 105 g. of a honey-yellow viscous liquid, B.P.=202-203° C./1.5 mm. Hg. The yield is 69% (theoretical quantity 152 g.).

Example 2.—Ethyl alpha-(1-naphthylmethyl)alpha-tetrahydrofurylpropylmalonate

$C_{25}H_{32}O_5$. (M=412.51.) Developed formula:

Sodium ethoxide is prepared from 4.5 g. (0.2 atom) of sodium and 128 cc. of absolute ethanol. There are added thereto 54.4 g. (0.2 mol.) of ethyl tetrahydrofurylpropylmalonate. The mixture is boiled for 5 minutes and then cooled. There are then added drop-by-drop 35.2 g. (0.2 mol.) of 1-chloromethylnaphthalene and the mixture is heated under reflux for 24 hours. After extraction, distillation gives 53 g. of a pale yellow viscous oil, B.P.=211° C./0.95 mm. Hg. Yield 64.7% (theoretical quantity 82 g.).

Example 3.—Alpha-(1-naphthyl)furylpropionitrile

$C_{17}H_{13}NO$. (M=247.27.)

Into a well-dried spherical flask are introduced 580 cc. of dry ether, 57 g. of 90% sodamide (1.26 mol. of $NaNH_2$) and 196 g. (1.17 mol.) of alpha-1-naphthylacetomitrile, whereafter the mixture is heated under reflux for one hour. The flask is cooled in an ice bath and there are added drop-by-drop 157 g. (1.34 mol.) of furfuryl chloride dissolved in 157 cc. of dry ether. After heating under reflux for 6 hours, the product is carefully poured into water and acidulated with hydrochloric acid. On distillation, there are obtained 208 g. of pale yellow viscous liquid distilling at 193-196° C./3 mm. Hg. Yield 71.8% (theoretical quantity 289.2 g.). After re-distillation, the product has the following constants:

B.P.=194-195° C./2 mm. Hg.

Refractive index: $n_d^{22}=1.611$.

It crystallises at ambient temperature.

After two recrystallisations from a mixture of ethanol and hexane in equal volumes, there is obtained a white solid having a melting point of 46.5–48° C. (on the heating-stage microscope).

Gravimetric analysis gives.—Calculated: C percent, 82.58; H percent, 5.29; N percent, 5.66. Found C percent, 82.21, 82.99; H percent, 5.33, 5.33; N percent, 5.45, 5.27.

Example 4.—Alpha-(1-naphthyl)tetrahydrofurylpropionitrile

$C_{17}H_{17}ON$. (M=251.31.)

41.2 g. (0.25 mol.) of tetrahydrofuryl bromide are condensed with 37.5 g. (0.224 mol.) of alpha-(1-naphthyl)acetonitrile by the same procedure as in Example 3.

After distillation, there are obtained 37.5 g. of pale yellow viscous liquid distilling at 184–187° C./1 mm. Hg.

Yield 67% (theoretical quantity 56.4 g.). After redistillation, the product has a boiling point of 154° C./0.4 mm. Hg.

Gravimetric analysis.—Calculated: C percent, 81.29; H percent, 6.82; N percent, 5.57. Found: C percent 81.01, 81.14; H percent, 6.63, 6.79; N percent 6.05, 6.10.

Example 5.—Alpha-(1-naphthyl)tetrahydrofurylvaleronitrile

$C_{19}H_{21}ON$. (M=279.36.)

62.2 g. (0.373 mol.) of 1-naphthylacetonitrile are condensed with 18.5 g. of 90% sodamide (0.425 mol. of $NaNH_2$) in 185 cc. of dry ether by the procedure of Example 4. There are added drop-by-drop 80 g. (0.439 mol.) of tetrahydrofurylpropylbromide in 80 cc. of dry ether. After distillation, there are obtained 73.3 g. of slightly turbid, very viscous, yellow liquid distilling at 192–194° C./0.5 mm. Hg. Yield 60%. The redistilled product has the following constants:

B.P./0.4 mm. Hg=183° C.

Gravimetric analysis.—Calculated: C percent, 81.70; H percent, 7.57; N percent, 5.01. Found: C percent, 81.83; H percent, 7.72; N percent, 5.14.

Example 6.—Alpha-(1-naphthyl)hexen-delta-4-oic nitrile

$C_{16}H_{15}N$. (M=221.28.)

11.1 g. of 90% sodamide (0.238 mol. of $NaNH_2$) in 110 cc. of dry ether are reacted as in Example 3 with 37.5 g. (0.224 mol.) of alpha-(1-naphthyl)acetonitrile and 33 g. (0.244 mol.) of crotyl bromide. There are obtained 32.5 g. of viscous yellow liquid. Yield 65.7%.

(theoretical quantity 49.5 g.). After two redistillations, the product has the following constants:

B.P. /0.9 mm. Hg=138° C.

Gravimetric analysis.—Calculated: C percent, 86.88; H percent, 6.83; N percent, 6.33. Found: C percent, 86.52; H percent, 6.97; N percent, 6.69.

Sodium methylate may be employed as condensing agent instead of sodamide.

Example 7.—Alpha-(1-naphthyl)penten-delta-4-oic nitrile

$C_{15}H_{13}N$. (M=207.25.)

11.1 g. of 90% sodamide (0.238 mol. of $NaNH_2$) in 110 cc. of dry ether are reacted as in Example 3 with 37.5 g. (0.224 mol.) of 1-naphthylacetonitrile and 28 g. (0.223 mol.) of allyl bromide.

The addition of allyl bromide takes place in an ice bath, and the reaction is violent.

Distillation of the final product gives 39.5 g. of pale yellow liquid distilling at 160° C./1.5 mm. Yield 85.6%. The redistilled product has the following constants:

B.P./0.4 mm.=130° C.

B.P./0.5 mm.=132° C.

Density: $D_4^{21}=1.0520$.

Refractive index: $n_D^{19.5}=1.603$.

Gravimetric analysis.—Calculated: C percent, 86.94; H percent, 6.31; N percent, 6.76. Found: C percent, 86.94, 86.87; H percent, 6.29, 6.15; N percent, 7.11, 7.04.

Example 8.—Beta-(1-naphthyl)beta'-furylisobutyric acid

$C_{18}H_{16}O_3$. (M=280.31.)

11 g. (0.196 mol.) of caustic potash in 860 cc. of benzyl alcohol and 38 g. (0.1 mol.) of ethyl alpha-(1-naphthylmethyl)alpha-furylfurylmalonate are heated under reflux for 15 hours. The reaction mixture, treated in the usual way, gives 19 g. of viscous liquid distilling at 207–209° C./1.5 mm. Hg. Yield 68% (theoretical quantity 28 g.).

When the extraction is effected with benzene instead of ether, the yield is 72%.

The product, covered with a layer of hexane, crystallises rapidly, after scraping of the wall with a rod, into substantially white crystals. The recrystallisation is effected as follows:

18 g. of crystals are dissolved in 18 cc. of tepid ethyl acetate. After filtration, 90 cc. of hexane are added to the solution and the mixture is placed in the refrigerator. The oil which precipitates is converted, after initiation of the crystallisation, in the form of a white crystalline mass having a melting point of 72–74° C. (heating stage) and an acid number of 198 (theoretical number 199).

Its sodium salt has a melting point of 260–262° C. (capillary tube).

Gravimetric analysis of the acid.—Calculated: C percent, 77.11; H percent, 5.75. Found: C percent 77.21, 77.04; H percent 5.63, 5.78.

Example 9.—Methyl beta-(1-naphthyl)beta-furylisobutyrate

$C_{19}H_{18}O_3$. (M=294.33.)

25 g. (0.089 mol.) of beta-(1-naphthyl)beta'-furylisobutyric acid are esterified by heating under reflux with 150 cc. of absolute methanol in the presence of 0.5 cc. of concentrated sulphuric acid.

Distillation of the product obtained gives 19.5 g. of pale yellow viscous liquid distilling at 197–200° C./4 mm. Hg. After redistillation, the ester possesses the following constants:

B.P./2 mm. Hg=193–195° C.

$D_4^{25}=1.333$

$n_D^{23}=1.583$

Saponification number.—Calculated: 190. Found: 182.

Example 10.—Neopentyl beta-(1-naphthyl)beta'-furylisobutyrate

Empirical formula $C_{23}H_{26}O_3$. (M=350.44.) Developed formula

21 g. (0.075 mol.) of beta-(1-naphthyl)beta'-furylisobutyric acid, which is a compound prepared as described in Example 8, in solution in 150 cc. of dry benzene is heated under reflux for 17 hours with 7 g. (0.0805 mol.) of neopentyl alcohol in the presence of 0.5 g. of paratoluenesulphonic acid. After the usual treatment of the reaction mixture, distillation gives 0.5 g. (yield about 32%) of very viscous yellow liquid distilling at 187–192° C./2 mm. Hg.

The redistilled product has the following constants:

B.P./2 mm. Hg=179–180° C.

Refractive index $n_D^{23.5}=1.5585$

Saponification number.—Calculated: 159. Found: 163.

Example 11.—N-diethylaminoethyl beta-(1-naphthyl)beta'-furylisobutyrate

$C_{24}H_{28}O_3N$. (M=379.47.)

In a spherical flask provided with a Dean and Stark decanting device, 28 g. (0.1 mol.) of beta-(1-naphthyl)beta'-furylisobutyric acid in 170 cc. of dry xylene, 12 g. (0.1025 mol.) of diethylaminoethanol and 0.5 g. of paratoluenesulphonic acid are heated under reflux for 5 hours. After the usual treatment, distillation gives 21 g. of very viscous dark yellow liquid distilling at 195–196° C./1 mm. Hg with decomposition. (Yield 60.5%).

After redistillation, there is obtained a product distilling at 188–190° C. under less than 1 mm.

$n_D^{21}=1.5728$

Gravimetric analysis.—Calculated: C percent, 75.98; H percent, 7.70; N percent, 3.69. Found: C percent, 74.74, 74.86; H percent, 7.32, 7.38; N percent, 3.49, 3.54.

Example 12.—Alpha-(1-naphthylmethyl)delta-tetrahydrofurylvaleric acid

$C_{20}H_{24}O_3$. (M=312.39.)

40.5 g. (0.098 mol.) of ethyl alpha-(1-naphthylmethyl)alpha-tetrahydrofurylpropylmalonate are saponified by a procedure similar to that of Example 8. There are obtained 23.5 g. of very viscous pale yellow oil distilling at 220–222° C. under less than 1 mm. (Yield 77%).

Acid number.—Calculated: 179. Found: 177.

Gravimetric analysis.—Calculated: C%, 76.89; H%, 7.74. Found: C%, 76.60, 76.50; H%, 7.38, 7.32.

The sodium salt has a melting point of 261° C. with decomposition (on the capillary tube). It is a hygroscopic product.

Example 13.—Methyl alpha-(1-naphthylmethyl)delta-tetrahydrofurylvalerate

$C_{21}H_{26}O_3$. (M=326.42.)

26.5 g. (0.0845 mol.) of alpha-(1-naphthylmethyl)delta-tetrahydrofuryl valeric acid are esterified by the procedure of Example 9.

Distillation of the product obtained gives 16 g. of viscous yellow oil distilling at 188–188.5° C. under about 1 mm. Hg. Yield: 57.7%.

The redistilled product has the following constants:

B.P./0.6 mm. Hg=178° C.

$D_4^{24}=1.182$

Saponification number—Calculated: 171. Found: 170.

Example 14.—Alpha-(1-naphthyl)furylpropionic acid

$C_{17}H_{14}O_3$. (M=266.28.)

40 g. (0.705 mol.) of potassium hydroxide in 1660 cc. of benzyl alcohol are heated under reflux for 15 hours with 79 g. (0.32 mol.) of 1-naphthyl-alpha-(furyl) acetonitrile. When the reaction is complete, the benzyl alcohol is driven off in vacuo and the solid residue is dissolved in water. The product is made acid with hydrochloric acid until it changes the colour of Congo red and is then extracted with benzene. Distillation gives 56.5 g. of viscous yellow liquid, B.P./2 mm. Hg 218–219° C. Yield 71.3%. Saponification gives the same yield if equimolecular quantities of nitrile and potassium hydroxide are employed.

The pasty product, covered with a layer of ether, crystallises after several hours in a refrigerator, to give almost white crystals. After three recrystallisations from ethyl

acetate or a mixture of ethyl acetate and hexane, the product has the following constants:

M.P.=80-82° C. (heating stage).

Acid number.—Calculated: 210. Found: 212.

Gravimetric analysis.—Calculated: C%, 76.70; H%, 5.30. Found: C%, 76.71, 76.78; H%, 4.94, 5.18.

The sodium salt takes the form of white crystals which are insoluble in cold water and soluble in boiling water, and which have a melting point of 302-303° C. (heating stage).

Saponification in ethanol, with stoichiometric quantities of nitrile and potassium hydroxide is longer (about a hundred hours). It gives a mixture of the same acid and of the corresponding amide.

The alpha-(1-naphthyl)furylpropionic amide is obtained alone by the procedure described in the following Example 15, which consists in hydrolysing nitrile in ethanol in the presence of the stoichiometric quantity of potassium hydroxide and limiting the duration of the reaction to half that necessary for producing the acid.

Example 15.—Alpha-(1-naphthyl)furylpropionamide

$C_{17}H_{15}NO_2$. (M=265.29.)

4.4 g. (0.079 mol.) of caustic potash in 5 cc. of water and 120 cc. of alcohol are heated under reflux for 50 hours with 19.5 g. (0.79 mol.) of 1-naphthyl-alpha-(furyl)acetonitrile. When the reaction is complete, the ethanol is evaporated in *vacuo*. The cooled mixture is acidulated with hydrochloric acid. The oily product is extracted with ether. After evaporation of the ether, there remains a solid residue, which is recrystallised from ethanol. There are obtained as the first fraction 2 g. of slightly yellow crystals, and then as the second fraction 1.5 g. of slightly brown crystals (total yield 50.2%). After two further recrystallisations, the product takes the form of white crystals having a melting point of 107-108° C. (heating-stage microscope).

Gravimetric analysis.—Calculated: C%, 77.00; H%, 5.70; N%, 5.28. Found: C%, 77.26, 77.11; H%, 5.85, 5.74; N%, 5.37, 5.43.

Example 16.—Methyl alpha-(1-naphthyl)furylpropionate

$C_{18}H_{16}O_3$. (M=280.31.)

27 g. (0.101 mol.) of alpha-(1-naphthyl)furylpropionic acid, 150 cc. of absolute methanol and 0.5 cc. of concentrated sulphuric acid are heated under reflux for 6½ hours. After the usual treatment, distillation gives 19 g. of pale yellow oil distilling at 172-172.5° C./1 mm. Hg.

Yield 67%.

The redistilled product possesses the following constants:

B.P./0.7 mm. Hg=158° C.

B.P./0.75 mm. Hg=159° C.

$D_{4}^{24}=1.1375$

$n_D^{23}=1.596$

Saponification number.—Calculated: 199. Found: 199.

Example 17.—Neopentyl alpha-(1-naphthyl)furylpropionate

$C_{22}H_{24}O_3$. (M=336.41.)

15 27 g. (about 0.1 mol.) of alpha-(1-naphthyl)furylpropionic acid, prepared as described in Example 14, is treated as in Example 10 with neopentyl alcohol. Distillation gives 16.5 g. (yield 49%) of a pale yellow oil distilling at 184-185° C./2 mm. Hg.

The redistilled product has the following constants:

B.P./1 mm. Hg=171-172° C.

$n_D^{21}=1.561$

Density: $d_4^{21}=1.0652$

25 Saponification number.—Calculated: 166. Found: 169.

Example 18.—N-diethylaminoethyl alpha-(1-naphthyl)furylpropionate

$C_{23}H_{27}O_3N$. (M=365.45.)

35 27 g. (0.101 mol.) of alpha-(1-naphthyl)furylpropionic acid in 170 cc. of dry xylene are esterified as in Example 11 with 12 g. (0.1025 mol.) of diethylaminoethanol in the presence of 0.5 g. of p-toluenesulphonic acid.

40 Distillation gives 17 g. of reddish-yellow viscous liquid distilling at 210-212° C./1 mm. Hg. Yield 46%. The redistilled product is pale yellow. Its constants are:

B.P./1.5 mm. Hg=215-216° C.

$n_D^{24}=1.5745$

45 Gravimetric analysis.—Calculated: C%, 75.60; H%, 7.44; N%, 3.83. Found: C%, 75.61, 75.30; H%, 7.08, 7.09; N%, 3.73, 3.70.

Example 19.—2-alpha-(1-naphthyl)furylpropionamido-ethanol

$C_{19}H_{19}NO_3$. (M=309.34.)

55 25 g. (0.089 mol.) of methyl alpha-(1-naphthyl)furylpropionate, prepared as described in Example 16, are heated under reflux for 16 hours with 11 g. (0.182 mol.) of monoethanolamine, 20 cc. of isopropanol and 0.4 cc. of acetic acid. After evaporation in *vacuo* of the volatile products, the viscous residue, transferred into a beaker, crystallises in a refrigerator. There are obtained 27 g. (yield 87.5%) of a pale yellow solid mass. After four recrystallisations from ethyl acetate and ethanol, the product takes the form of white crystals having the following constants:

70 M.P.=122-123° C. (heating stage).

11

Acetyl number.—Calculated: 181. Found: 181.
 Analysis.—Calculated: C%, 73.77; H%, 6.19; N%, 4.52. Found: C%, 73.59; H%, 6.11; N%, 4.62.

Example 20.—*Alpha-(1-naphthyl)tetrahydrofurylpropionic acid*

$C_{17}H_{18}O_3$. ($M=270.31$.)

65 g. (0.259 mol.) of alpha-(1-naphthyl)tetrahydrofurylpropionitrile are hydrolysed as in Example 14. After the usual treatment of the crude reaction product, an oil separates, which rapidly solidifies in the refrigerator (31.5 g.). The mother liquors are extracted with benzene and the extract is distilled. There are thus recovered 15 g. of viscous product distilling at 217–218° C./1.5 mm. Hg. The total yield is 66.5%.

The preceding distillate is taken up in 25 cc. of ethyl acetate, and white crystals are formed on the addition of hexane. After three recrystallisations, the product takes the form of white crystals having a melting point of 135° C. (heating stage).

Acid number.—Calculated: 207. Found: 207.

Gravimetric analysis.—Calculated: C%, 75.53; H%, 6.71. Found: C%, 75.57; H%, 6.62.

The sodium salt has a melting point of 250–251° C. (capillary tube).

Example 21.—*Alpha-(1-naphthyl)tetrahydrofurylpropionamide*

$C_{17}H_{19}NO_2$. ($M=269.32$.)

15.5 g. (0.0617 mol.) of alpha-(1-naphthyl)tetrahydrofurylpropionitrile are hydrolysed as in Example 15. After the usual treatment and evaporation of the extraction solvent (benzene), there remain 12.5 g. (yield 75%) of a crystalline mass.

After two recrystallisations from ethyl acetate, the product has the following constants:

M.P.=153–153.5° C.

Gravimetric analysis.—Calculated: C%, 75.83; H%, 7.11; N%, 5.20. Found: C%, 75.62; H%, 7.14; N%, 5.14.

Example 22.—*Methyl alpha-(1-naphthyl)tetrahydrofurylpropionate*

$C_{18}H_{20}O_3$. ($M=284.34$.)

22 g. (0.0812 mol.) of alpha-(1-naphthyl)tetrahydrofurylpropionic acid are esterified as in Example 9. There are obtained 17.5 g. of pale yellow viscous liquid (yield 75.5%). The redistilled product has a boiling point of 157–158° C./0.36 mm. Hg.

Saponification number.—Calculated: 196. Found: 200.

5

12

Example 23.—*Neopentyl alpha-(1-naphthyl)tetrahydrofurylpropionate*

$C_{22}H_{28}O_3$. ($M=340.44$.)

10

15

27 g. (0.1 mol.) of alpha-(1-naphthyl)tetrahydrofurylpropionic acid, prepared as described in Example 20, are esterified with neopentyl alcohol. Distillation gives 20 g. (yield about 59%) of viscous yellow liquid distilling at 182–185° C./1 mm. Hg.

20

The redistilled product has the following constants: B.P./1 mm. Hg=182–185° C.

Saponification number.—Calculated: 164. Found: 164.

Example 24.—*N-diethylaminoethyl alpha-(1-naphthyl)tetrahydrofurylpropionate*

$C_{23}H_{31}NO_3$. ($M=369.48$.)

35

40

27 g. (0.1 mol.) of alpha-(1-naphthyl)tetrahydrofurylpropionic acid are esterified in the manner described in Examples 11 and 12 with 12 g. (0.1 mol.) of diethylaminoethanol. There are obtained 19 g. (yield 51.5%) dark yellow oil distilling at 191–194° C./0.5 mm. Hg.

45

The redistilled product, which has a honey-yellow color, has a melting point of 191° C./0.36 mm. Hg.

Gravimetric analysis.—Calculated: C%, 74.79; H%, 8.46; N%, 3.79. Found: C%, 74.86, 74.57; H%, 8.34, 8.51; N%, 3.98, 3.92.

Example 25.—*Alpha-(1-naphthyl)delta-tetrahydrofurylvaleric acid*

$C_{19}H_{22}O_3$. ($M=298.37$.)

60

65

143.5 g. (0.515 mol.) of alpha-(1-naphthyl)delta-tetrahydrofurylvaleronitrile are hydrolysed in a manner similar to that described in Example 14 with 31.6 g. (0.565 mol.) of caustic potash in solution in 1500 cc. of benzyl alcohol.

70

Distillation of the mixture obtained gives 88 g. of very viscous yellow liquid distilling at 214–216° C./0.4 mm. Hg. Yield 57.5%. The redistilled product has the following constants:

B.P./0.35 mm. Hg=210° C.

Acid number.—Calculated: 186. Found: 187.

Gravimetric analysis.—Calculated: C%, 7.49; H%, 7.43. Found: C%, 76.39; H%, 7.24.

75

13

Example 26.—Diethylaminoethyl alpha-(1-naphthyl)-delta-tetrahydrofurylvalerate

$C_{25}H_{35}NO_3$. ($M=397.53$.)

29.8 g. (0.1 mol.) of alpha-(1-naphthyl)tetrahydrofurylvaleric acid, prepared as described in Example 22, are esterified with diethylaminoethanol by the procedure described in Example 11.

Distillation gives 20 g. (yield 50.5%) of brownish-yellow viscous liquid distilling at 216° C./0.7 mm. Hg and at 218–219° C./0.85 mm. Hg.

The redistilled product has the following constants:

B.P./0.6 mm. Hg=216° C.
 $n_D^{22}=1.5555$

Analysis.—Calculated: C%, 75.53; H%, 8.87; N%, 3.52. Found: C%, 75.33; H%, 8.63; N%, 3.45.

Example 27.—Beta-(1-naphthyl)beta'-tetrahydrofuryl-isobutyric acid

$C_{18}H_{20}O_3$. ($M=284.34$.)

This compound is prepared from ethyl alpha-(1-naphthylmethyl)alpha-tetrahydrofurfurylmalonate, which is itself a new compound (B.P.=200° C./1 mm. Hg) obtained by the general process of preparation hereinbefore defined, by condensation of ethyl tetrahydrofurfurylmalonate and 1-chloromethylnaphthalene in the presence of sodium ethoxide.

62 g. (0.161 mol.) of ethyl alpha-(1-naphthylmethyl)-alpha-tetrahydrofurfurylmalonate are saponified as indicated in Example 8. Distillation gives 23 g. (yield about 50%) of very viscous brownish-yellow liquid distilling at 216–220° C./1 mm. Hg. The redistilled product has the following constants:

B.P./1 mm. Hg=212° C.

Acid number.—Calculated: 197. Found: 194.

Analysis.—Calculated: C%, 76.05; H%, 7.09. Found: C%, 76.76, 76.72; H%, 6.60, 6.66.

Example 28.—(1-naphthyl)hexen-delta-4-oic acid

$C_{16}R_{16}O_2$. ($M=240.29$.)

67 g. (0.3 mol.) of alpha-(1-naphthyl)hexen-delta-4-oic nitrile are hydrolysed as in Example 14. Distillation of the product gives 41 g. of pale yellow viscous liquid. After distillation, the product has the following constants:

B.P./0.7 mm. Hg: 167° C.
B.P./0.8 mm. Hg: 168° C.

Acid number.—Calculated: 233. Found: 234.

14

Gravimetric analysis.—Calculated: C%, 80.00; H%, 6.71. Found: C%, 80.13; H%, 6.75.

Example 29.—Alpha-(1-naphthyl)hexen-delta-4-oic amide

$C_{16}H_{17}NO$. ($M=239.30$.)

15 22 g. (0.1 mol.) of alpha-(1-naphthyl)hexen-delta-4-oic nitrile are hydrolysed by the procedure of Example 15. There are obtained 21 g. of yellow product (yield 87.7%). After four recrystallisations from ethyl acetate, the product has a melting point of 121–122° C. It sublimes in the neighbourhood of this temperature.

16 Gravimetric analysis.—Calculated: C%, 80.30; H%, 7.16; N%, 5.85. Found: C%, 80.43; H%, 7.30; N%, 6.03.

Example 30.—Methyl alpha-(1-naphthyl)hexen-delta-4-oate

$C_{17}H_{18}O_2$. ($M=254.31$.)

35 24 g. (0.1 mol.) of alpha-(1-naphthyl)hexen-delta-4-oic acid, prepared as described in Example 28, are esterified with methyl alcohol by the procedure of Example 9.

Distillation gives 19 g. (yield 75%) of viscous yellow liquid distilling at 131–134° C./1 mm. Hg.

The redistilled product has the following constants:

$d_4^{22}=1.0616$

$n_D^{22}=1.5825$

Saponification number.—Calculated: 224. Found: 224.

Example 31.—Diethylaminoethyl alpha-(1-naphthyl)hexen-delta-4-oate

$C_{22}H_{29}O_2N$. ($M=339.45$.)

55 24 g. (0.1 mol.) of alpha-(1-naphthyl)hexen-delta-4-oic acid are esterified with diethylaminoethyl alcohol by the procedure described in Example 11.

60 Distillation gives 15 g. (yield 44%) of honey-yellow viscous liquid distilling at 205–207° C./3 mm. Hg.

The pale yellow redistilled product has the following constants:

65 B.P./2 mm. Hg=197° C.

$d_4^{22}=1.020$

$n_D^{22}=1.564$

Analysis.—Calculated: C%, 77.85; H%, 8.61; N%, 4.12. Found: C%, 78.10, 78.28; H%, 8.27, 8.24; N%, 3.98, 3.95.

70 This compound may be solubilised by salification with an acid, more especially hydrochloric acid. It can be directly obtained in the form of its chloride by heating the starting acid with beta-chloroethyl-N-diethylamine in isopropanol.

15

Example 32.—*Alpha-(1-naphthyl)hexen-delta-4-oic hydrazide*

$C_{16}H_{18}N_2O$. (M=254.32.)

25.5 g. (0.1 mol.) of methyl *alpha*-(1-naphthyl)hexen-delta-4-oate, the preparation of which has been described in the foregoing Example 30, are heated under reflux for 4½ hours with 20.4 g. (0.4 mol.) of 98% hydrazine hydrate, in solution in 45 cc. of isopropyl alcohol (the mixture is heterogeneous in the cold) in the presence of 0.4 cc. of acetic acid.

When the reaction is complete, the volatile products are driven off in *vacuo*. The desired product is deposited in the form of a white crystalline mass, which is dried in the air. There are obtained 23.5 g. (yield 92.5%) of white product. After three recrystallisations from ethyl acetate, the product has the following constants:

M.P.=125-127° C. (heating stage), with sublimation starting at 100° C.

Analysis.—Calculated: C%, 75.58; H%, 7.13; N%, 11.03. Found: C%, 75.81; H%, 7.24; N%, 10.91.

Example 33.—*Alpha-(1-naphthyl)penten-delta-4-oic acid*

$C_{15}H_{14}O_2$. (M=226.26.)

29 g. (0.14 mol.) of *alpha*-(1-naphthyl)penten-delta-4-oic nitrile are hydrolysed as described in Example 14. Distillation of the product gives 17.5 g. of faintly coloured, very viscous liquid which distills at 162-164° C./0.7 mm. Hg (yield 55%). The redistilled product has the following constants:

B.P./0.6 mm. Hg=157-158° C.

Acid number.—Calculated: 2.47. Found: 246.

Gravimetric analysis.—Calculated: C%, 79.60; H%, 6.23. Found: C%, 79.08, 79.12; H%, 6.00, 6.12.

Example 34.—*Diethylaminoethyl ester of alpha-(1-naphthyl)penten-delta-4-oic acid*

Empirical formula $C_{21}H_{27}NO_2$. (Molecular mass: M=325.42.) Developed formula:

23 g. (0.1 mol.) of *alpha*-(1-naphthyl)penten-delta-4-oic acid, in solution in 230 cc. of isopropanol and 14 g. (0.104 mol.) of beta-chloroethyl-N-diethylamine are heated under reflux for 8½ hours. After evaporation of the isopropanol in *vacuo* on the water bath, the syrupy residue is taken up in a potassium carbonate solution and the organic product is separated by extraction with ether. Distillation gives 23 g. of a pale yellow viscous liquid distilling under 4 mm. Hg at 194-195° C. (yield=71%).

The redistilled product has the following physical constants:

B.P./1 mm. Hg=148-149° C.

Density: $d_4^{23}=1.0205$

Refractive index: $n_D^{24}=1.555$

Gravimetric analysis.—Calculated: C%, 77.76; H%, 7.75

16

8.08; N%, 4.31. Found: C%, 77.50; H%, 8.04; N%, 4.50.

Example 35.—*Dimethylaminoethyl ester of alpha-(1-naphthyl)penten-delta-4-oic acid*

Empirical formula $C_{19}H_{23}NO_2$. (M=297.37.)

In an apparatus provided with a Dean and Stark device, 23 g. (0.1 mol.) of *alpha*-(1-naphthyl)penten-delta-4-oic acid in solution in 150 cc. of anhydrous toluene, 9 g. (0.101 mol.) of dimethylaminoethanol and 0.5 g. of paratoluene sulphonic acid are heated under reflux for 20 hours. Distillation gives 5 g. of pale yellow viscous liquid distilling under 3 mm. Hg at 182° C. After redistillation, the product has the following boiling point:

B.P./1.5 mm. Hg=166-168° C.

Gravimetric analysis.—Calculated: C%, 76.76; H%, 7.79; N%, 4.71. Found: C%, 76.99; H%, 7.59; N%, 4.80.

We claim:

1. A compound of the formula

in which

35 n , is an odd number at most equal to 3, R_1 is a member of the group consisting of the 1-naphthyl and 1-naphthylmethyl radicals, and R_2 is a member of the group consisting of the furyl and tetrahydrofuryl radicals and—when n denotes the number 1 and R_1 the naphthyl radical—the vinyl and 1-propenyl radicals.

2. A sodium salt of a compound of the formula

in which

n , is an odd number at most equal to 3, R_1 is a member of the group consisting of the 1-naphthyl and 1-naphthylmethyl radicals, and R_2 is a member of the group consisting of the furyl and tetrahydrofuryl radicals and—when n denotes the number 1 and R_1 the naphthyl radical—the vinyl and 1-propenyl radicals.

3. Beta-(1-naphthyl) beta'-furylisobutyric acid.

4. Alpha-(1-naphthyl) methyl delta-tetrahydrofuryl valeric acid.

5. Alpha-(1-naphthyl)-beta-furylpropionic acid.

6. Alpha - (1-naphthyl)-beta-tetrahydrofurylpropionic acid.

7. Alpha - (1-naphthyl)-delta-tetrahydrofuryl valeric acid.

8. Beta - (1-naphthyl) beta'-tetrahydrofurylisobutyric acid.

9. Alpha-(1-naphthyl) delta-4-hexenoic acid.

10. Alpha-(1-naphthyl) delta-4-pentenoic acid.

11. Process for the production of a compound according to claim 1, which comprises hydrolysing under reflux, for at least 10 hours, an alpha-substituted nitrile of the formula

in which n , R_1 and R_2 have the same meanings as in claim 1, by an alkali in the presence of benzyl alcohol.

12. An ester of a compound according to claim 1 of the formula

in which n , R_1 and R_2 have the same meanings as in claim 1 and R_3 denotes a member of the group consisting of the alkyl containing at most five carbon atoms and dilower alkylaminoethyl radicals.

13. The methyl ester of the acid according to claim 3.

14. Diethylaminoethyl beta-(1-naphthyl) beta-furyl-isobutyrate.

15. The methyl ester of the acid according to claim 4.

16. The methyl ester of the acid according to claim 5.

17. Diethylaminoethyl alpha-(1-naphthyl) beta-furyl-propionate.

18. The methyl ester of the acid according to claim 6.

19. Diethylaminoethyl alpha-(1-naphthyl) beta-tetrahydrofurylpropionate.

20. Diethylaminoethyl alpha-(1-naphthyl) delta-tetrahydrofurylvalerate.

21. The methyl ester of the acid according to claim 9.

22. Diethylaminoethyl alpha-(1-naphthyl)delta-4-hexenoate.

23. Diethylaminoethyl alpha-(1-naphthyl)delta-4-pentenoate.

24. Neopentyl beta-(1-naphthyl)-beta'-furylisobutyrate.
25. Neopentyl alpha-(1-naphthyl)-beta-furylpropionate.
26. Neopentyl alpha-(1-naphthyl)-beta-tetrahydrofuryl-propionate.
